UNITED STATES PATENT OFFICE.

WILLIAM BUTLER AND ZALMON G. SIMMONS, JR., OF KENOSHA, WISCONSIN.

BALLAST-LOADING APPARATUS.

SPECIFICATION forming part of Letters Patent No. 447,460, dated March 3, 1891.

Application filed September 22, 1890. Serial No. 365,821. (No model.)

To all whom it may concern:

Be it known that we, WILLIAM BUTLER and ZALMON G. SIMMONS, Jr., citizens of the United States, residing at Kenosha, in the county of 5 Kenosha and State of Wisconsin, have invented a new and useful Improvement in Ballast-Loading Apparatus, of which the following is a specification.

A well-known method of making ballast for 10 the road-beds of railways is that of burning clay in the open air, and thus producing a long hill or pile of the burned ballast. This pile is produced by periodically supplying to it layers of clay dug from a trench formed by 15 the digging along one side of the pile or "fire." The manner of proceeding is such as to increase the width of the pile on the side thereof adjacent to the trench, while at the same time increasing its height. Thus the finishing 20 of the ballast takes place, as it were, from the side of the pile opposite that adjacent to the trench, and which may be termed the "outer side," thereby enabling the burnt product to be taken for use from the outer 25 side of the pile while the burning is being continued at the opposite side. Hitherto the loading of this burned ballast for shipment has been performed by hand, requiring the work of a large number of men in transferring 30 it to the means of transportation from the outer side of the pile, thereby rendering the work expensive and of slow progress.

The object of our invention is to provide 35 an apparatus for effecting in a sense automatically the transfer of ballast from the pile to cars for transporting it, thereby to enable the work to be performed rapidly and at comparatively little cost.

Our invention consists in the construction 40 of the apparatus, adapting it to our purpose.

The accompanying drawing is in the nature of a diagram, representing the outer side of a ballast-burning fire and showing our improved apparatus in elevation, partly sectional, as in operative position with relation 45 to the pile.

A is a car on a track r , extending along the outer or burnt side of the pile B. Between the track r and the pile B is another track q 50 for cars C to be loaded with ballast from the pile. Inside the car B are supported winding-drums p and o , which may be driven by

machinery or by hand-power, and adjacent to the drums are the pivotal levers n , each having a brake-shoe n' to fit its respective drum, 55 against which it is normally held by a spring m .

The car A supports on its roof a mast structure D, from the base of which extends toward the pile B a boom E, which, while it may be rigid, is shown as being pivoted to the 60 base k of the mast and sustained by a cable l , attached at one end to the outer end of the boom, extending thence over a pulley l' on the upper end of the mast and fastened at its outer end to the base k .

F is a scoop comprising a bucket i , open at its top and forward and rear ends, from the base of the forward of which ends extends a beak h . The bucket is pivotally supported at one side of its center at x in a frame g , 70 which surrounds the body of the bucket, and is provided at or near its center with a rigid bail f . At its forward end the frame is extended into an upwardly-inclined handle e , and at its rear end it is extended 75 upward into a bearing e' , at which to pivot a latch d , normally engaging a catch d' on the body of the bucket to secure it in operative position in the frame. A cable c is fastened at one end to the handle e , and passes thence 80 over a guide-pulley c' on the outer end of the boom and a guide-pulley c'' on the mast to the drum p . A cable b is fastened at one end to the bail f and passes thence over a pulley b' on the top of the mast to the drum o .

By manipulating the levers n to force the brake-shoes n' away from the winding-drums the cables may pay out to permit the scoop F to be lowered to or toward the base of the pile B. By then winding up the cable c the scoop 90 is dragged in the direction away from the car A up the inclined side of the pile, thereby filling itself with ballast. When so filled, the cable b is wound on the drum o to pull the scoop over the car C, (the cable c then being 95 allowed to pay out,) when, if necessary, the scoop is lowered by causing the cable b to pay out and the latch d released from its catch, thereby causing the bucket i to dump its contents on the car C. Thus, as will readily be seen, the loading of the ballast is performed rapidly and easily.

Obviously our improved apparatus may be used for loading other substances than bal-

last—as coal and the like—in piles; and we do not desire to be understood as limiting it to the loading of the burnt ballast.

What we claim as new, and desire to secure 5 by Letters Patent, is—

1. In a loading apparatus substantially for the purpose set forth, a car A on a track *r*, extending along the burnt side of a pile B, a mast D on the roof of the car, having a boom E extending toward the pile, winding mechanism on the car, and a scoop connected with the winding mechanism by a cable *c* to control the scoop to be dragged up the side of the pile in the direction away from the car, 10 and by a cable *b* for hoisting the scoop, substantially as described.

2. In a loading apparatus, a car A on a track *r*, extended along the burnt side of a pile B, a mast D on the roof of the car, having a boom E extending toward the pile, a scoop F, comprising a bucket *i*, pivotally supported eccentrically in a frame *g* and having a beak *h* at its forward end and a catch *d'*, and a handle *e*, bail *f*, and latch *d* on the 15 frame, winding-drums *o* and *p* on the car, a cable *c*, connecting the scoop from the frame *g* with the drum *p* and passing over guide-pulleys *c'* and *c²*, and a cable *b*, connecting

the scoop from its bail *f* with the drum *o* and passing over a guide-pulley *b'* on the mast, 20 the whole being constructed and arranged to operate substantially as described.

3. A loading apparatus comprising, in combination, a car A on a track *r*, extended along the burnt side of a pile B, a mast D on the 25 roof of the car, having a boom E extending from it toward the pile, a scoop F, comprising a bucket *i*, pivotally supported eccentrically in a frame *g* and having a beak *h* at its forward end and a catch *d'*, and a handle *e*, bail *f*, and latch *d* on the frame, winding-drums *o* and *p* on the car, spring-controlled levers *n*, carrying brake-shoes for the drums, a cable *c*, connecting the scoop from the frame *g* with the drum *p* and passing 30 over guide-pulleys *c'* and *c²*, and a cable *b*, connecting the scoop from its bail *f* with the drum *o* and passing over a guide-pulley *b'* on the mast, the whole being constructed and arranged to operate substantially as de- 35 scribed.

WILLIAM BUTLER.

ZALMON G. SIMMONS, JR.
